CONTACT LENS CARRYING CASE

Paul A. Hoogesteger, Penfield, and John Kadlecik, Macedon, N.Y., assignors to Bausch & Lomb Incorporated, Rochester, N.Y.

Filed July 22, 1974, Ser. No. 490,537

Term of patent 14 years

Int. Cl. D16—06

U.S. Cl. D57—1 B

FIG. 1

FIG. 2

FIG. 3

FIG. 1 is a perspective of a contact lens carrying case as viewed from the designated top showing our new design;

FIG. 2 is a plan view of the designated bottom of our new design; and

FIG. 3 is an end view thereof.

The side and end views not shown have essentially the same appearance as those shown.

We claim:

The ornamental design for a contact lens carrying case, substantially as shown and described.
